UNITED STATES PATENT OFFICE.

JAMES O. JACKSON, OF DENVER, COLORADO.

FLASH-LIGHT GUN.

Application filed November 17, 1921. Serial No. 515,843.

To all whom it may concern:

Be it known that I, JAMES O. JACKSON, a citizen of the United States, residing at the city and county of Denver and State 5 of Colorado, have invented certain new and useful Improvements in Flash-Light Guns; and I do declare the following to be a full, clear, and exact description of the invention such as will enable others skilled in the 10 art to which it appertains to make and use the same, reference being had to the accompanying drawings, and to the characters of reference marked thereon, which form a part of this specification.

15 This invention relates to flash lights and has special reference to a gun or revolver by means of which the flash light powders can be conveniently exploded.

In taking photographs, it is, of course, 20 essential that the object to be photographed is sufficiently well illuminated. In order to enable photographs to be taken at night, on dark days, or in dark rooms, it is customary to illuminate the object by means of burning 25 magnesium powder, or what is generally referred to as "flash light powder". Various means and methods have been devised and used for conveniently handling and 30 igniting the flash light powders, some of which have been used with a greater or less amount of success.

It is the object of this invention to provide 35 means for handling and igniting flash light powders that shall be conveniently operated, and which will be so designed that it will be possible to explode a single powder or several in quick succession.

In order to more clearly describe my invention, I shall make reference to the 40 accompanying drawing in which

Fig. 1 shows my improved flash light gun in side elevation, with parts thereof shown in section;

Fig. 2 is a front view thereof;

45 Fig. 3 is a longitudinal section of the cartridge containing the flash light powder;

Fig. 4 shows a modified form of barrel; and

50 Fig. 5 is a view showing my device in operation.

The same reference characters will be used to indicate the same parts throughout the several views.

My device consists of an ordinary re-

volver of suitable caliber, such as .44 or .50, 55 from which the barrel has been removed and replaced by a barrel of special design. In the drawing 1 represents the hand grip, 2 the trigger, 3 the hammer, and 4 the revolving cylinder, all of which are assembled and operate in the usual way. The barrel is of special construction and comprises a cylindrical portion 5 which is attached to the frame of the revolver in the manner of any ordinary barrel. My barrel, 60 instead of being a cylinder throughout, is flattened and widened, in the manner indicated by the portion designated by numeral 6 in Figs. 1, 2 and 3, and terminates in a flat thin opening 7 which is arranged trans- 70 verse to the vertical plane of the revolver handle in the manner shown in Fig. 2.

The flash light powders 8 are packed within an ordinary copper or paper cartridge 9, which is provided with an ordinary percussion primer 10. The powder is held in place within the cartridge by means of a piece of wadding 11 of any suitable material, but preferably composed of wax. The end of the shell is crimped slightly, as 80 shown at 12, for the purpose of holding the wadding in place.

My device is operated in the same manner as any ordinary revolver, the charge 8 of flash light powder being ignited by the 85 action of the percussion cap 10; the burning powder will then be forced out through the flattened end of the barrel and will produce a fan-shaped flare 13. Since the wad 11 is made of wax, it will be melted by the 90 intense heat and will pass out into the atmosphere in a molten or gaseous state.

In Fig. 4 I have shown a slightly modified form of opening in the discharge end 95 of the barrel, the elongated opening 7^A being somewhat narrowed at its central point whereby there will result a greater tendency to spread the vapors as they emerge from the pistol.

From the above it will be seen that I have 10 provided a flash light gun that can be conveniently carried and operated, and which will enable the operator to explode several charges in rapid succession if he finds it necessary.

I am aware that the results aimed at by me may be attained by means that may be specifically different from that disclosed by

me, and I desire that my disclosure shall be taken in an illustrative and not in a limiting sense.

Having now described my invention, what 5 I claim as new is:

A flash light gun comprising a chamber adapted to contain a flash light powder, means adapted to ignite the powder, an extended barrel communicating with said

chamber, said barrel extending in the same 10 general direction as the chamber, the end of the barrel that connects with the chamber having a cylindrical opening, while the other and outer end has a long narrow opening constricted at its center. 15

In testimony whereof I affix my signature.

JAMES O. JACKSON.
